MASTER-CONTROL APPARATUS

Application filed January 29, 1930. Serial No. 424,258.

My invention relates to master control apparatus, and is particularly suitable for, though not limited to, apparatus for controlling traffic governing devices such as switches and signals in a railway interlocking plant.

One feature of my invention is the provision of means, comprising a master lever controlled by a slow-acting device, for releasing electric locking for a plurality of control levers instead of by the common method of using a separate slow-acting device for releasing each control lever such, for example, as in a usual railway interlocking plant.

I will describe three forms of master control apparatus embodying my invention, and will then point out the novel features thereof in claims.

In the accompanying drawings, Fig. 1 is a diagrammatic view showing one form of master control apparatus embodying my invention. Figs. 2 and 3 are diagrammatic views showing modifications of portions of the apparatus of Fig. 1, and each also embodying my invention.

Similar reference characters refer to similar parts in each of the views.

Referring first to Fig. 1, the reference characters 1, 1^a, 1^b and 1^c designate the track rails of a stretch of double track railway. The two tracks are interconnected through a crossover track Y and switches H¹ and H². Rails 1 and 1^a are divided by insulated joints 2 to form sections A—B and B—C. Rails 1^b and 1^c are divided by insulated joints 2 to form sections D—E and E—F. Section A—B is connected with a siding Z by a switch H³. Each of these track sections is supplied with current by a battery 3 connected across the rails adjacent one end of the section, and is provided with a track relay designated by the letter G with a distinguishing exponent and connected across the rails adjacent the opposite end of the section.

Signals designated by the letter S with distinguishing exponents govern traffic movements over switches H¹, H² and H³. Signals S¹ and S² govern eastbound moves, that is, moves toward the right, as shown in the drawing, over switch H¹ normal and reversed, respectively. Signal S³ governs westbound

moves over switch H¹ in its normal position, and signal S⁴ governs westbound moves over switch H² reversed or switch H² normal and switch H² normal. As shown in the drawing, each of these signals is of the semaphore type. 55 Signals S¹, S², S³ and S⁴ operate contacts 20, 19, 21 and 39, respectively, each of which is closed when and only when its signal is indicating "stop."

Switches H¹, H² and H³ may be operated 60 in any suitable manner as controlled by manually operable levers V¹ and V². The control and operating circuits for these switches form no part of my present invention, and are hence omitted from the drawing. The 65 operation of switches H¹ and H² is controlled by lever V¹, and the operation of switch H³ is controlled by lever V². Each of these levers has a normal position n, a reverse position r, and two lock positions b and d. Lever V¹ 70 operates six contacts, contacts 13 and 55 of which are closed only while lever V¹ is in its n position; contacts 14 and 57 of which are closed only while lever V¹ is in its r position; contact 4 of which is closed while lever V¹ 75 is in its n or its d position or at any intermediate point; and contact 6 of which is closed while lever V¹ is in its b or its r position or at any intermediate point. Lever V² operates contact 13 which is closed when 80 lever V² occupies its n position only, and contact 14 which is closed while lever V² occupies its r position only.

The signals S are controlled by levers V³ and V⁴, each of which has a normal position 85 h, a reverse position f to the left, a reverse position t to the right, a lock position a to the left, and a lock position i to the right of the normal position h. Lever V³, when in its f position, controls signals S², and, when in its t position, controls signal S¹ or S² according as lever V¹ is in its n or its r position for controlling switches H¹ and H². Lever V⁴, when in its f position, controls signal S⁴. Lever V³ 90 operates two contacts 23 and 24, each of which is closed when lever V³ occupies its i position only; contact 53 which is closed when lever V³ is in its t position only; contact 59 which is closed when lever V³ 95 is in its f position only; and contact 87 which 100

is closed while lever V^3 is in its f or its h or any intermediate position. Lever V^4 operates contact 72 which is closed when lever V^4 is in its f position only.

The manual operation of lever V^1 is controlled by two electric lock magnets L^1 and L^3 , respectively, as in a common form of railway interlocking machine. Each of these electromagnets, when energized, attracts a dog 61, as shown for magnet L^1 , and, when deenergized, permits its dog 61 to fall against a segment 62 which is operated by lever V^1 , as shown for magnet L^3 . When lever V^1 is moved toward its r position, both of its segments 62 are moved toward the left along an arc of a circle. The segment for magnet L^1 is provided with a stop 63 which, if its dog 61 is down when movement of lever V^1 is attempted while lever V^1 is in its n position, will engage its dog 61, preventing movement of lever V^1 away from the n position. The segment for magnet L^3 is provided with a stop 64, which, if its dog 61 is down when movement of lever V^1 is attempted while lever V^1 is in the r position, will engage its dog 61, preventing movement of lever V^1 away from its r position. Stop 64 also checks, at position b , the movement of lever V^1 toward its r position, and stop 63 checks, at position d , the movement of lever V^1 toward its n position, except as controlled by the usual switch indication apparatus which forms no part of my present invention and which is therefore omitted from the drawing. The manual operation of lever V^2 is controlled by magnets L^2 and L^4 similarly to the manner in which lever V^1 is controlled by magnets L^1 and L^3 as just described. Magnets L^1 and L^3 for lever V^1 are controlled by track relays G^1 and G^3 for the sections in which switches H^2 and H^1 , respectively, are located. Magnets L^2 and L^4 for lever V^2 are controlled by relay G^2 for the section in which switch H^2 is located.

Magnets L^1 and L^3 can also, at times, be controlled by a manually operable push button contact 52 in series with a contact 50 which is operated by a master lever V^5 . Magnets L^2 and L^4 can, at times, be controlled also by a manually operable push button contact 49 in series with a contact 47 which is operated by master lever V^5 . Push button contacts 49 and 52 are normally open, being closed only when manually depressed, and returning to the open position when not manually held down. Master lever V^5 has three positions, a normal position n , a reverse position r , and a lock position m . Lever V^5 operates a segment 68 which, by a cam 70, controls as low-acting device not shown in the drawing and, by a shoulder 69, is in turn controlled by the slow-acting device through a rod 71 which is rigidly connected with a dog 84. Lever V^5 operates four contacts including contacts 47 and 50 which are closed when

lever V^5 is in its r position only, and contacts 37 and 45 which are closed when lever V^5 is in its n position only. The slow-acting device is associated with lever V^5 as already stated, and the method of control of the slow-acting device by lever V^5 and the method of control of lever V^5 by the slow-acting device may be similar to those disclosed and claimed in Letters Patent of the United States No. 1,310,500, granted to W. P. Neubert, July 22, 1919.

The manual operation of lever V^3 is controlled by an electric lock magnet M^1 as in common railway interlocking systems. Magnet M^1 , when energized, attracts its dog 61, and, when deenergized, permits its dog 61 to fall against a segment 66 which is operated by lever V^3 . When lever V^3 is moved toward its f position, segment 66 is moved toward the right along an arc of a circle, and when lever V^3 is moved toward its t position, segment 66 is moved toward the left along an arc of the same circle. Segment 66 is provided with a stop 67 which, when its dog 61 is down, engages dog 61 and checks the movement of lever V^3 at position a or i when lever V^3 is moved from its f or its t position, respectively, toward its h position. Lever V^3 is thus arrested until magnet M^1 becomes energized and lifts its dog 61 away from stop 67. Lever V^4 is controlled by its magnet M^2 similarly to the manner in which lever V^2 is controlled by magnet M^1 as just described. Magnets M^1 and M^2 are controlled in part by contacts operated by master lever V^5 , and in part by the contacts operated by the signals.

A stick relay T is controlled by track relays G^1 and G^3 and by levers V^1 and V^3 . Relay T enters into the control of magnet M^1 of lever V^3 .

A time releasing device U^1 , which may be of the clockwork type, is employed in the usual manner for releasing the approach locking of lever V^3 by magnet M^1 . A similar releasing device U^2 is also employed in the usual manner for releasing the stick locking of lever V^4 by magnet M^2 .

Although not shown in the drawing, it is to be understood that lever V^3 , when moved away from its h position, mechanically locks lever V^1 . It is also to be understood that lever V^4 , when moved away from its h position, mechanically locks lever V^1 , and when lever V^1 is in its normal position n , lever V^4 locks lever V^2 in its n position.

In Fig. 2, section B—C, switch H^2 and signal S^4 are shown as in Fig. 1. Lever V^4 , as shown in Fig. 2, is, however, controlled by two electric lock magnets M^3 and M^4 instead of by the single magnet M^2 , shown in Fig. 1. Lever V^4 here has a second lock position e to the left, and a second lock position h to the right of the normal position h , and therefore has a total of seven instead of the five positions shown in Fig. 1. Lever V^4 , by its

contact 72, controls signal S^4 as in Fig. 1. A segment 66 for each of the magnets M^3 and M^4 , respectively, is operated by lever V^4 . Segment 66 for magnet M^3 has a stop 74 which arrests lever V^4 at its positions a or i after the beginning of its movement from the f or the t position, respectively, toward the h position. Segment 66 for magnet M^4 has a stop 75 which arrests lever V^4 at its positions e or k when lever V^4 is moved from the a or the i position, respectively, toward the h position.

Lever V^5 has three positions as in Fig. 1 but operates only two contacts, 79 which is closed when lever V^5 is in its r position only, and contact 80 which is closed when lever V^5 is in its n position only. Segment 68, which is operated by lever V^5 , has, in Fig. 2, a cam 77 and a shoulder 76 which are so arranged that lever V^5 is arrested when it is being returned from its r to its n position, instead of when it is being moved from its n to its r position as shown in Fig. 1.

In Fig. 3, all parts are as in Fig. 2, except that lever V^5 has two additional contacts, 82 which is closed while lever V^5 is in its m or its r or any intermediate position, and contact 83 which is closed while lever V^5 is in its n or its m or any intermediate position. Contacts 82 and 83 complete additional branch paths in the control circuits for magnets M^4 and M^3 , respectively.

Having thus described, in general, the arrangement and location of the various parts comprising my invention, I will now trace the operation of the apparatus.

As shown in the drawings, all parts are in their normal condition, that is, track sections A—B, B—C, D—E and E—F are uncoupled, switches H^1 , H^2 and H^3 are in their normal position, signals S^1 , S^2 , S^3 and S^4 are indicating "stop", levers V^1 , V^2 and V^3 are in their n position, and levers V^3 and V^4 are in their h position. Each of the track relays G is therefore energized. Referring to Fig. 1, with lever V^1 in its n position and track relay G^3 energized, relay T is energized by its circuit passing from terminal x of a source of current not shown in the drawing, through contact 4 of lever V^1 , wire 5, contact 9 of relay G^3 , winding of relay T , wire 86, and contact 87 of lever V^3 to terminal o of the same source of current. A branch path is also closed passing from the winding of relay T , through contact 85 of relay T , to terminal o . With relays G^1 and G^3 energized and lever V^1 in its n position, magnet L^1 is energized by its circuit passing from terminal x , through contact 10 of relay G^3 , contact 11 of relay G^1 , wire 12, contact 13 of lever V^1 , and the winding of magnet L^1 to terminal o . With relay G^2 energized and lever V^2 in its n position, magnet L^2 is energized by its circuit passing from terminal x , through contact 15 of relay G^2 , wire 16, contact 13

of lever V^2 , and the winding of magnet L^2 to terminal o .

I will assume that, with all parts thus in their normal condition, the leverman moves lever V^3 to its t position for clearing signal S^1 . The arm of signal S^1 is then operated to its "proceed" position by its circuit passing from terminal x , through contact 53 of lever V^3 , wire 54, contact 55 of lever V^1 , wire 56, and the mechanism of signal S^1 to terminal o . Lever V^3 , upon being moved to its t position, mechanically locks lever V^1 .

If an east bound train now enters section E—F and stops in section E—F clear of the crossover, and if the leverman then desires to reverse switches H^1 and H^2 , he will return lever V^3 as far as its i position where it will be checked by dog 61 of lever V^3 until the arm of signal S^1 has moved to its stop position and closed its contact 20. With contact 20 closed, magnet M^1 will be energized by its circuit passing from terminal x , through contact 19 of signal S^2 , contact 20 of signal S^1 , contact 21 of signal S^3 , wire 22, contact 23 of lever V^3 , wire 24, contact 25 of relay G^4 , wires 30 and 36, contact 37 of lever V^5 , wire 38, and the winding of magnet M^1 to terminal o . Relay G^3 is deenergized by the train in section E—F, and hence a branch path is also closed, passing from contact 21 of signal S^2 , through wires 26 and 27, and contact 28 of relay G^3 to wire 30. Magnet M^1 now lifts dog 61, and the leverman then resumes the movement of lever V^3 to its h position, mechanically unlocking lever V^1 . With relay G^3 deenergized, contact 10 of relay G^3 is open, and hence magnet L^1 is deenergized, thus preventing movement of lever V^1 to its r position.

The leverman will therefore move lever V^5 to its m position where it will be checked by dog 84 coming against shoulder 69 of segment 68. After the lapse of a measured interval of time, a slow-acting device lifts rod 71 and so moves dog 84 away from shoulder 69. The leverman will then continue the movement of lever V^5 to its r position. He will then close push button contact 52, thus completing a second circuit for magnet L^1 passing from terminal x , through contact 50 of lever V^5 , wire 51, contact 52, contact 13 of lever V^1 , and the winding of magnet L^1 to terminal o . The leverman will now reverse lever V^1 to cause switches H^1 and H^2 to be moved to their reverse positions. The leverman can now again move lever V^3 to its t position, thereby completing a circuit for signal S^2 passing from terminal x , through contact 53 of lever V^3 , wire 54, contact 57 of lever V^1 , wire 58, and the mechanism of signal S^2 to terminal o .

If relay T is still deenergized on account of relay G^3 being deenergized, or if it becomes deenergized due to an eastbound train passing signal S^2 and entering section E—F,

lever V^3 cannot again be returned to its h position until lever V^5 has been returned to its n position. This is because relay T , after having become deenergized, cannot again become energized until lever V^3 has been returned to its h position and has closed its contact 87 which is in series with the winding of relay T . The leverman will therefore return lever V^5 to its n position, thereby closing its contact 37. If relay G^4 is energized, magnet M^1 will now be energized by its circuit previously traced through contact 25 of relay G^4 , and hence lever V^3 can be returned to its h position. Relay T now becomes energized by a second pick-up circuit passing from terminal x , through contact 6 of lever V^1 , wire 7, contact 8 of relay G^1 , contact 9 of relay G^3 , winding of relay T , wire 86, and contact 87 of lever V^3 to terminal o . With lever V^1 in its r position when relays G^1 and G^3 are both energized, magnet L^3 becomes energized by its circuit passing from terminal x , through contact 10 of relay G^3 , contact 11 of relay G^1 , wire 12, contact 14 of lever V^1 , and the winding of magnet L^3 to terminal o . With magnet L^3 energized, lever V^1 can now be moved away from its r position.

When the circuit for magnet M^1 , as first traced, is open at contact 25 of relay G^4 , it can become closed, when relay G^3 is deenergized, as in usual approach locking circuits by a branch path passing from contact 21 of signal S^3 , through wires 26 and 27, and contact 28 of relay G^3 to wire 30 as previously traced. Another branch path around contact 25 passes from contact 21 of Signal S^3 , through wire 26, and contact 29 of releasing device U^1 to wire 36, as in the usual arrangement for releasing the approach locking for a signal lever.

Lever V^2 is controlled by its magnets L^2 and L^4 similarly to the manner in which lever V^1 is controlled by magnets L^1 and L^3 , as just described, and its control will therefore be readily understood from the drawing without further description. Lever V^4 is controlled by its magnet M^2 similarly to the manner in which lever V^3 is controlled by its magnet M^1 , except that there is no branch path around contact 45 of lever V^5 in the circuit for magnet M^2 as there is around contact 37 of lever V^5 in the circuit for magnet M^1 . The control of lever V^4 will therefore be readily understood from the drawing.

I will now assume that lever V^1 is in its n position, and that hence switches H^1 and H^2 are in the normal position, and that lever V^3 has been moved to its t position for causing the arm of signal S^1 to occupy its "proceed" position. I will also assume that relay G^2 is deenergized, and that the leverman has started to reverse lever V^5 in order to release the electric locking of lever V^2 to permit operation of switch H^3 from one posi-

tion to the other. I will further assume that before the interval of time has elapsed as required for the operation of the slow-acting device for lifting the rod 71 to move dog 84 out of engagement with shoulder 69 of segment 68 of lever V^5 , the leverman desires to return lever V^3 to its h position. With lever V^1 in its n position, and assuming that relay G^3 is energized, relay T will be energized by its circuit previously traced through contact 4 of lever V^1 . Lever V^5 having been moved away from its n position, its contact 37 is open, and hence the circuits for magnet M^1 of lever V^3 previously traced through contact 37 are open.

When the leverman moves lever V^3 from its t to its i position, contact 34 operated by lever V^3 will become closed and hence, relay T being energized, magnet M^1 will now be energized by a circuit passing from terminal x , through contact 19 of signal S^2 , contact 20 of signal S^1 , contact 21 of signal S^3 , wire 22, contact 23 of lever V^3 , wire 24, contact 25 of relay G^4 , assuming that relay G^4 is energized, wire 31, contact 32 of relay T , wire 33, contact 34 of lever V^3 , wires 35 and 38, and the winding of magnet M^1 to terminal o . With magnet M^1 energized, the leverman can now return lever V^3 to its h position although lever V^5 has been moved away from its n position preparatory to releasing lever V^2 .

I will next assume that with all parts again in their normal condition as shown in Fig. 2, the leverman clears signal S^4 by moving lever V^4 to its f position and thus closing its contact 72 in the operating circuit for signal S^4 which passes from terminal x , through contact 72, wire 73, and the mechanism of signal S^4 to terminal o . If, before a train has passed signal S^4 , the leverman should desire to change the position of any of the switches over which traffic is controlled by signal S^4 , he will move lever V^4 from its f to its a position, and will then move lever V^5 to its r position, thereby completing a circuit for magnet M^3 passing from terminal x , through contact 39 of signal S^4 , wire 78, contact 79 of lever V^5 , and the winding of magnet M^3 to terminal o . With the magnet M^3 energized, dog 61 for magnet M^3 is lifted out of engagement with stop 74, and hence the leverman can move lever V^4 as far as its e position where it will be checked by dog 61 for magnet M^4 engaging stop 75 of segment 66 for magnet M^4 . The leverman will now return lever V^5 as far as its m position where it will be checked by dog 84 engaging shoulder 76 of segment 68 of lever V^5 . Upon the lapse of a measured interval of time, the releasing device associated with lever V^5 will raise rod 71, thereby removing dog 84 from engagement with shoulder 76, and the leverman will then continue the movement of lever V^5 to its n position. With lever V^5 in its n position, magnet M^4 will be energized by

120
125
130

its circuit passing from terminal α , through contact 80 of lever V^5 , and the winding of magnet M^4 to terminal σ . The movement of lever V^4 to its h position can then be completed to permit the operation of the desired switch lever.

If, when the leverman has cleared signal S^4 by moving lever V^4 to its f position as previously described, a train enters section B—C, deenergizing relay G^1 , and if the leverman then returns lever V^4 to its a position, opening its contact 72 and so causing the arm of signal S^4 to fall to its stop position, magnet M^3 for lever V^4 will become energized by a circuit passing from terminal α , through contact 39 of signal S^4 , wire 40, contact 41 of relay G^1 , and the winding of magnet M^3 to terminal σ . If lever V^5 is in its n position, magnet M^4 is energized as already described, and hence lever V^4 can now be returned to its h position.

With the arrangement shown in Fig. 3, lever V^4 can be returned to its h position by means of the procedure and under the conditions just described in connection with Fig. 2, except that the circuit for magnet M^4 as well as the circuit for magnet M^3 includes contact 39 of signal S^4 . If, on the other hand, lever V^5 has been moved to its reverse position in order to release some other signal lever than V^4 and has been returned as far as its m position, lever V^4 , when relay G^1 is deenergized, can be returned to its h position while lever V^5 is still in its m position, magnet M^3 being then energized by its circuit passing from terminal α , through contact 39 of signal S^4 , wire 40, contact 41 of relay G^1 , wire 81, contact 83 of lever V^5 , and the winding of magnet M^3 to terminal σ . Magnet M^4 is, at the same time, energized by its circuit which follows the path just traced for magnet M^3 as far as wire 81, thence through contact 82 of lever V^5 , and the winding of magnet M^4 to terminal σ . It is thus clear that with the arrangement of Fig. 3, lever V^4 can be returned to its h position if relay G^1 is deenergized, although lever V^5 is being manipulated to release some other signal lever.

It is to be understood that, although in Figs. 2 and 3 I have shown circuits for controlling only one signal lever V^4 by master lever V^5 , exactly similar circuits can be used for controlling each one of a plurality of other signal levers as well as lever V^4 by lever V^5 .

From the foregoing description and the accompanying drawings, it is clear that as shown in Fig. 1 my invention provides a master lever for releasing any one of a plurality of switch levers when the track relay for the section in which the switch is located is deenergized. It is also clear that a given interval of time must elapse between the return of a signal lever to its normal

position and the release of a switch lever which is associated with the signal lever.

It is clear that, in Figs. 2 and 3, my invention provides means for releasing the approach or stick locking for each one of a plurality of signal levers. With the arrangement of Fig. 2, master lever V^5 , when reversed to release a given signal lever, does not prevent any other signal lever from being reversed for clearing a signal and does not prevent the operation of any switch which is not in the route controlled by the signal lever which is being released by the master lever. It is also clear that with the arrangements shown in Figs. 2 and 3, when lever V^5 is being employed to release a signal lever, a given interval of time, as controlled by the slow-releasing device which is associated with lever V^5 , must elapse during the return of the signal lever from one of its reverse positions to its normal position h .

Fig. 3 provides for still more flexibility of operation than does Fig. 2. With the circuits shown in Fig. 3, the operation of master lever V^5 , when releasing any given signal lever, does not prevent the control of any other signal lever by its usual releasing circuit through a back contact of a track relay in the route governed by the signal.

Although I have herein shown and described only three forms of master control apparatus embodying my invention, it is understood that various changes and modifications may be made therein within the scope of the appended claims without departing from the spirit and scope of my invention.

Having thus described my invention, what I claim is:

1. In combination, a railway track switch, a signal for governing the movement of traffic over said switch, a manually operable signal lever having a normal and a reverse position, means for clearing said signal when said signal lever is moved to its reverse position, a manually operable master lever having a normal and a reverse position, a manually operable switch lever having a normal and a reverse position for controlling the operation of said switch to its normal and reverse positions respectively, a normal electric lock which when deenergized locks said switch lever in its normal position, a reverse electric lock which when deenergized locks said switch lever in its reverse position, means for energizing said switch lever locks when said master lever is in its reverse position, and means for preventing the movement of said signal lever from its reverse to its normal position except when said master lever is in its normal position.

2. In combination, a railway track switch, a signal for governing the movement of traffic over said switch, a manually operable sig-

- nal lever having a normal and a reverse position, means for clearing said signal when said signal lever is moved to its reverse position, a manually operable master lever having a normal and a reverse position, a manually operable switch lever for controlling the operation of said switch, an electric lock which when deenergized prevents movement of said switch lever to control said switch, means for energizing said electric lock when said master lever is in its reverse position, and means for preventing the movement of said signal lever to its normal position except when said master lever is in its normal position.
3. In combination, a plurality of railway track switches, a plurality of signals each of which governs the movement of traffic over one or more of said switches, a plurality of manually operable signal levers each having a normal and a reverse position, means for clearing each of said signals when one of said signal levers is moved to its reverse position, a manually operable master lever having a normal and a reverse position, means for controlling the operation of each of said switches to its normal or its reverse position when said master lever is in its reverse position, and means for preventing the movement of each of said signal levers from its reverse to its normal position except when said master lever is in its normal position.
4. In combination, a railway track switch, a signal for governing the movement of traffic over said switch, a manually operable signal lever having a normal and a reverse position, means for clearing said signal when said signal lever is moved to its reverse position, a manually controllable slow-acting device having a normal and a reverse position, means for controlling the operation of said switch when said slow-acting device is in its reverse position, and means for preventing the movement of said signal lever from its reverse to its normal position except when said slow-acting device is in the normal position.
5. In combination, a railway track switch, a signal for governing the movement of traffic over said switch, a manually operable signal lever having a normal and a reverse position, means for clearing said signal when said signal lever is moved to its reverse position, a manually controllable device having a normal and a reverse position and which can be moved quickly from its reverse to its normal position but which enforces the lapse of a measured interval of time during movement from its normal to its reverse position, means for controlling the operation of said switch when said device is in its reverse position, and means for preventing the movement of said signal lever to its normal position except when said device is in its normal position.
6. In combination, a plurality of railway

signals for governing a plurality of traffic movements, a plurality of manually operable signal levers each having a normal and a reverse position, means for clearing each of said signals when one of said signal levers is moved to its reverse position, an electric lock for each of said signal levers and which when deenergized prevents movement of its lever to the normal position, a manually controllable device having a first and a second position, means for deenergizing said electric locks when said device is in said first position, and means for energizing said electric locks when said device is in said second position.

7. In combination, a railway signal, a manually operable signal lever having a normal and a reverse position, means for clearing said signal when said lever is moved to its reverse position, a manually controllable device having a normal and a reverse position, means for permitting part only of the return of said signal lever from its reverse to its normal position when said device is in its reverse position, and means for permitting the completion of such return of the signal lever when said device is moved to its normal position.

8. In combination, a railway signal, a manually operable signal lever, means controlled by said lever for controlling said signal, a manually controllable slow-acting device, means for arresting the movement of said lever at a first and a second locking point, means controlled by said device for permitting said lever to be moved quickly past said first locking point, and means controlled by said device for permitting said lever to be moved past said second locking point only upon the lapse of a given period of time after said lever is moved past said first locking point.

9. In combination, a railway signal, a manually operable signal lever, means controlled by said lever for controlling said signal, a first and a second locking point for said lever, an electromagnet, a second electromagnet, means controlled by said first electromagnet for permitting said lever to be moved past said first locking point, means controlled by said second electromagnet for permitting said lever to be moved past said second locking point, a manually controllable device having a first and a second position, means controlled by said device in its first position for controlling said first electromagnet, and means controlled by said device in its second position for controlling said second electromagnet.

10. In combination, a railway signal, a manually operable signal lever, means controlled by said lever for controlling said signal, a first electric lock which when deenergized arrests the movement of said lever at a first locking point, a second electric lock which when deenergized arrests the movement of said lever at a second locking point,

5 a manually operable device having a first and a second position, means controlled by said device when in said first position for energizing said first electric lock, and means controlled by said device when in said second position for energizing said second electric lock.

10 11. In combination, a manually operable lever for controlling a railway signal, a first electric lock, a second electric lock, means controlled by said first and second electric locks for controlling said lever, a manually operable device having a first and a second position, means controlled by said device when in said first position for controlling said first electric lock, and means controlled by said device when in said second position for controlling said second electric lock.

15 12. In combination, a manually operable lever for controlling a railway signal, a first electric lock, a second electric lock, means controlled by said first and second electric locks for controlling said lever, a manually operable master lever having a first and a second position, means controlled by said master lever for controlling said electric locks, a slow-acting device controlled by said master lever, and means controlled by said device for so controlling said master lever that said lever can be moved quickly from its first to its second position but that said lever can be moved to its first position upon the lapse only of a given period of time after said lever has left its second position.

20 13. In combination, a stretch of railway track, a signal for controlling traffic movements into said stretch, a manually operable lever for controlling said signal, a first and a second electric lock, means controlled by said first and second electric locks for controlling said lever, a manually operable master lever having a first and a second position, means controlled by said master lever when in its second position for controlling said first electric lock, means controlled by said master lever when in its first position while said stretch of track is occupied for controlling said first electric lock, means controlled by said master lever when in its first position for controlling said second electric lock, and means controlled by said master lever when in its second position while said stretch of track is occupied for controlling said second electric lock.

25 14. In combination, a stretch of railway track, a signal for controlling traffic movements into said stretch, a manually operable lever for controlling said signal, a first and a second electric lock, means controlled by said first and second electric locks for controlling said lever, a manually operable master lever having a first and a second position, a slow-acting device controlled by said master lever, means controlled by said device for arresting the movement of said master

30 lever for a measured interval of time at a locking point between said first and second positions, means controlled by said master lever when in its second position for controlling said first electric lock, means controlled by said master lever when in its first position or at said locking point or at any intermediate point while said stretch of track is occupied for controlling said first electric lock, means controlled by said master lever when in its first position for controlling said second electric lock, and means controlled by said master lever when in its second position or at said locking point or at any intermediate point while said stretch of track is occupied for controlling said second electric lock.

35 15. In combination, a manually operable lever for controlling an electrical device, a first and a second electric lock for controlling said lever, a manually operable master lever having a normal and a reverse position, means controlled by said master lever in its normal position for controlling said first electric lock, and means controlled by said master lever in its reverse position for controlling said second electric lock.

In testimony whereof I affix my signature.

LESTER E. SPRAY.
